UNITED STATES PATENT OFFICE.

JOHN W. SMITH, OF BOSTON, MASSACHUSETTS.

HOBBY-HORSE.

SPECIFICATION forming part of Letters Patent No. 715,887, dated December 16, 1902.

Application filed May 22, 1902. Serial No. 108,446. (No model.)

To all whom it may concern:

Be it known that I, JOHN W. SMITH, a citizen of the United States, and a resident of Boston, county of Suffolk, State of Massachusetts, have invented an Improvement in Hobby-Horses, of which the following description, in connection with the accompanying drawings, is a specification, like letters on the drawings representing like parts.

10 This invention relates to hobby or rocking horses of the class wherein the body of a horse is mounted upon an upright supporting device adapted to oscillate in a vertical plane against spring action when the child seated upon the horse-body throws his weight to one or the other side of the normal upright position of the supporting device.

One of the objects of my present invention is to provide for ready vertical adjustment of 20 the carrier on which the horse-body is mounted to adapt the apparatus for children of different heights.

Another object of my invention is to simplify, strengthen, and improve the construction of the whole apparatus.

These and other novel features of my invention will be hereinafter described, and particularly pointed out in the following claims.

Figure 1 is a side elevation of a hobby-horse embodying one form of my invention, the casing for the lower part thereof being shown in vertical section. Fig. 2 is a vertical section in part on the line $x-x$, Fig. 1, the horse-body being omitted. Fig. 3 is a 35 transverse section on the line $x'-x'$, Fig. 1, looking down; and Fig. 4 is a perspective detail, enlarged, of the foot and lower end of the lower member of the carrier.

Referring to Figs. 1 and 2, a suitable supporting-stand a , which may be of cast-iron or other material, is shown as provided with a rigid upturned standard a' , bifurcated at its upper end and enlarged to form two opposite and parallel substantially circular cheeks 40 a^2 , which constitute a bearing for the carrier on which the horse-body or similar device H , Fig. 1, is mounted, and a pivot-pin a^3 is secured in the cheeks at their centers. The carrier is made longitudinally extensible or 45 adjustable in order that the height of the horse-body may be adjusted to children of different ages, and herein I have shown the

carrier as comprising two members B C . The member B or lower member is shown as an elongated bar having flanges b at its longitudinal edges and on opposite sides thereof to form between them longitudinal guide-grooves b^x (see Figs. 3 and 4) to receive the member C , said member being bifurcated for the greater part of its length to present two 55 separated and parallel legs c , which enter the guide-grooves b^x and slide longitudinally therein, the material of the member B between the flanges b entering between said legs. The member B is provided with a series of holes b' , adapted to receive a pin or bolt c' , which passes through opposite holes in the lower portion of the legs c of the member C to retain the two members of the carrier in relative adjusted position. The lower 60 end of the member B is shown as provided with a circular foot b^2 , (see Fig. 4,) having a central hole b^3 to receive the fulcrum-pin a^3 , said foot being interposed between the cheeks a^2 of the standard, and between the cheeks 65 the standard is concaved, as at a^4 , (see dotted lines, Fig. 1,) corresponding in curvature to the periphery of the foot. The carrier as a whole is thus adapted to oscillate or swing on its fulcrum a^3 in a vertical plane 70 intersecting said fulcrum at right angles thereto, the cheeks coöperating with the foot b^2 to firmly and securely support and provide a bearing for the carrier. If desired, the lower end of the carrier may be provided 75 with a short segmental flange b^4 on its opposite faces to ride upon the peripheries of the cheeks. I have shown herein a slot-and-pin limiting device to limit the amplitude of oscillation of the carrier, and I have shown a 80 segmental slot b^5 in the foot b^2 , concentric with its center, to be entered by a pin a^5 , passed transversely through and supported in the cheeks at the lower part thereof. The member C of the carrier has at its upper end 85 an enlargement or head C^x , on which the horse-body is secured in any suitable manner. 90

Referring to Fig. 1, the member B of the carrier is shown as provided on its fore-and-aft edges with depending and diverging arms 95 b^6 , which extend from at or near the upper end of said member down to a point preferably some little distance below the fulcrum a^3 , the lower edges of the arms resting on the

free ends of suitable springs S, herein shown as leaf-springs rigidly secured by screws or other fastenings s⁵ to the stand in front and at the back of the standard a', the springs 5 acting in opposite directions and their force being transmitted by or through the diverging and depending arms b⁶ on the carrier to a point well above its fulcrum. Manifestly the normal tendency of the springs is to center 10 the carrier and the parts mounted or supported thereupon in upright central position, (shown in Fig. 1,) and when the child is seated upon the horse-body he can by throwing his weight forward or back cause the carrier to 15 swing in one direction or the other, the spring toward which such movement is directed being compressed while the other spring relaxes, and vice versa. Relatively light springs may 20 be employed, and the movement of the horse-body will be easy, yet sufficiently lively or active to provide the requisite motion to the horse-body.

The lower portion of the apparatus is pref- 25 ably inclosed in a suitable casing, and in Fig. 1 the casing M is shown in section as sur- 30 rounding the springs and the bearing of the carrier, the said casing having an opening, as M', to permit the oscillating movement of the carrier.

30 The adjustment of the carrier vertically is readily and quickly effected, and the manner in which the two members of said carrier co- 35 operate provides for strength and rigidity with lightness.

35 My invention is not restricted to the pre- 40 cise construction and arrangement herein shown, as the same may be modified in dif- 45 ferent particulars by those skilled in the art without departing from the spirit and scope 50 of my invention.

Having fully described my invention, what I claim as new, and desire to secure by Letters Patent, is—

1. In a hobby-horse, a supporting-base, an 45 oscillating carrier pivotally mounted thereon, a horse-body or the like secured to the upper 50 end of the carrier, means to yieldingly and normally center the latter in upright position, and means to positively limit the swinging 55 movement of the carrier.

2. In a hobby-horse, a supporting-stand hav- 55 ing a standard provided with a bearing, a lon- 60 gitudinally-extensible carrier mounted in said bearing to oscillate in a vertical plane, a horse-body secured to the upper end of the carrier, oppositely-acting springs to coöper- 65 ate with and normally center the carrier in up- 70 right position, and means to positively limit the amplitude of oscillation of the carrier.

60 3. In a hobby-horse, a supporting-stand hav- 75 ing a standard, bifurcated at its upper end to present two parallel, circular cheeks, a car- 80 rier having a corresponding circular and flat-

tened foot interposed between the cheeks, a transverse pivot therethrough on which the 65 carrier swings in a vertical plane, oppositely-acting springs mounted on the stand and co-operating with the carrier, to normally maintain it in upright, central position, and a horse-body or the like secured to the upper 70 end of the carrier.

4. In a hobby-horse, a supporting-stand hav- 75 ing a standard bifurcated at its upper end to present two parallel, circular cheeks, a car- 80 rier having a corresponding circular and flat- 85 tened foot interposed between the cheeks, a transverse pivot therethrough on which the carrier swings in a vertical plane, a segmen- 90 tal slot in the foot concentric with its ful- 95 crum, a fixed pin extended into the slot, to limit oscillation of the carrier, and springs mounted on the stand and oppositely acting upon the carrier.

5. In a hobby-horse, a supporting-base, a lon- 85 gitudinally-adjustable, oscillating carrier piv- 90 otally mounted thereon, a horse-body or the like secured to the upper end of the carrier, diverging arms depending from the carrier above its pivot and in the path of movement 95 of the carrier, and springs mounted on the 100 stand in front of and behind the pivot respec- 105 tively and coöperating with said arms, to normally center the carrier in upright position.

6. In a hobby-horse, a supporting-stand hav- 95 ing a standard thereon, a two-part carrier piv- 100 otally mounted thereon to oscillate in a vertical plane, said carrier comprising a lower member having longitudinal guide-grooves on 105 its opposite sides, and a slide member bifur- 110 cated to embrace and slide in the guide- 115 grooves of the lower member, a device to maintain said members in adjusted relative position, a horse-body on the slide member, oppositely-acting springs mounted on the 120 stand in front of and behind the standard, and means to transmit the force of the springs to the carrier above its fulcrum or pivot.

7. In a hobby-horse, a supporting-base, a carrier pivotally connected at its lower end 110 with the stand, a horse-body or the like on the upper end of the carrier, the latter being oscillatable on its pivot in a vertical plane, leaf-springs on the stand and acting in op- 115 posite directions, and means to transmit the force of the springs to the carrier at a dis- 120 tance above its pivot, the springs acting to return the carrier to central, upright position when deflected therefrom.

In testimony whereof I have signed my 120 name to this specification in the presence of two subscribing witnesses

JOHN W. SMITH.
